(57) **CLAIM**

The ornamental design for an animal repeller, as shown and described.

DESCRIPTION

FIG. 1 is a front, bottom perspective view of an animal repeller showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, top perspective view thereof; and,

FIG. 9 is an enlarged detail view taken from portion 9 of FIG. 2.

The broken lines in the drawings depict portions of the animal repeller that form no part of the claimed design.
